Patented Aug. 15, 1967

208,306

COMBINED INPUT/OUTPUT AND VISUAL DISPLAY UNIT FOR A COMPUTER

Gregory F. Fossella, Marblehead, Mass., assignor to
Sanders Associates, Inc., Nashua, N.H.

Filed Sept. 30, 1965, Ser. No. 87,237

Term of patent 14 years

(Cl. D26—5)

FIG. 4

FIG. 1 is a perspective view of a combined input/output and visual display unit for a computer showing my new design;

FIG. 2 is a side elevational view of the same;

FIG. 3 is a front elevational view of the same; and

FIG. 4 is a perspective view of same, illustrating separability of the keyboard and display unit.

I claim:

The ornamental design for a combined input/output and visual display unit for a computer, as shown.
